UNITED STATES PATENT OFFICE.

OTTO W. SIEBENHAAR, OF LADOGA, WISCONSIN.

SPRING-TREAD HORSESHOE.

SPECIFICATION forming part of Letters Patent No. 657,298, dated September 4, 1900.

Application filed June 25, 1900. Serial No. 21,542. (No model.)

To all whom it may concern:

Be it known that I, OTTO W. SIEBENHAAR, a citizen of the United States, residing at Ladooga, in the county of Fond du Lac and State 5 of Wisconsin, have invented certain new and useful Improvements in Horseshoes; and I do hereby declare the following to be a full, clear, and exact description of the invention, such as will enable others skilled in the art to which 10 it appertains to make and use the same.

This invention has relation to the type of horseshoes having a yielding tread portion to relieve jar and prevent the attendant ailments to horses when driven over hard and 15 stony roads.

For a full description of the invention and the merits thereof, and also to acquire a knowledge of the details of construction of the means for effecting the result, reference is to 20 be had to the appended description and drawings hereto attached.

While the essential and characteristic features of the invention are not necessarily susceptible of modification, still the preferred 25 embodiment of the invention is illustrated in the accompanying drawings, in which—

Figure 1 is a plan view of the horseshoe as seen from the tread-surface. Fig. 2 is a side elevation. Fig. 3 is a perspective view of the 30 foot member. Fig. 4 is a perspective view of the tread member.

Corresponding and like parts are referred to in the following description and indicated in all the views of the drawings by the same 35 reference characters.

The horseshoe comprises the foot member 1 and tread member 2, the former being constructed either of wrought-iron or common steel and the latter of steel capable of being 40 tempered so as to resist wear and retain resiliency, which is essential to the effectiveness of the article when in service.

The tread member 2 is comparatively thin and light, and its toe and heel portions are 45 deflected away from the plane of the foot member 1 to provide spring portions 3 and 4. The intermediate portion of the tread member is thick and provided with openings 5 to receive the fastenings 6, by means of which 50 the members 1 and 2 are secured together, said fastenings being machine-screws and

having their heads countersunk in the lower face of the member 2. This construction admits of the tread member being readily replaced when worn or removed from the foot 55 member for any purpose when desired. In order to add to the life of the tread member and prevent slipping, it is provided at its toe and heel with the usual calks, which by preference form an integral part of the said member. 60 By having the toe and heel portions oppositely inclined or deflected the horseshoe as a whole is rendered yielding, so as to compensate for jar and prevent the usual ailments resulting from driving a horse over 65 hard and stony roads when shod with the common shoe.

In order to prevent gravel, dirt, and other foreign matter lodging in the angular spaces formed between the foot and tread members, 70 rubber blocks 7 and 8 are interposed between the spring portions 3 and 4 and the adjacent parts of the foot member 1. These rubber blocks in addition to excluding foreign matter from gaining access between the members 75 of the horseshoe supplement the spring action of the parts 3 and 4 and prevent any metallic ring incident to the steel tread member 2 striking a stone or like object.

The foot member 1 is comparatively thin 80 and is reinforced at its inner and outer edges by flanges 9, which also serve to retain the rubber blocks 7 and 8 against casual displacement. Nail-holes 10 are formed in the foot member 1 adjacent to the outer flange and 85 admit of the passage of the nails by means of which the horseshoe is attached to the foot in the well-known manner.

The tread member 2 has portions cut away from the outer edge of its legs, as shown at 90 11, to admit of the horseshoe-nails having unobstructed passage through the nail-holes 10 and to provide clearance for the heads of the nails when the horseshoe is in position. Inner and outer clips 12 are located at the toe 95 of the tread member 2 and coöperate with the flanges 9 at the toe portion of the member 1 and prevent either outward or inward displacement of the elastic block 7. The heel portions of the tread member are flanged to 100 provide seats 13, which act in conjunction with the adjacent flanged portions of the foot

member to retain the heel-cushioning blocks 8 in position.

The horseshoe is of composite structure, the foot member being of common stock, such as 5 wrought-iron or cheap steel, and the tread member 2 being of high-grade steel, so as to resist wear, retain its spring qualities, and be 10 comparatively light and durable. The foot member is permanently attached to the foot 15 and is removed only when it becomes necessary to trim the hoof. The tread member, being detachably connected with the foot member, can be readily removed to be replaced when worn or for any purpose found necessary.

Having thus described the invention, what is claimed as new is—

1. A composite horseshoe comprising a foot member having inner and outer flanges, a 20 tread member detachably connected with the foot member and having its toe portion deflected away from the plane of the foot member and formed with inner and outer clips, and an elastic block located between the toe

portions of the two members and held in 25 place by the flanges and clips thereof, substantially as set forth.

2. The herein-described composite horseshoe comprising a foot member having inner and outer flanges and a series of nail-openings adjacent to the outer flange, a tread member having its heel and toe portions oppositely deflected and flanged and having the intermediate portion thick and cut away at its outer edge to clear the nail-holes of the 30 foot member, fastenings detachably connecting the foot and tread members, and elastic blocks of wedge form secured in the angular spaces formed between the toe and heel portions of the members and prevented from 35 casual displacement by the corresponding flanges thereof, substantially as set forth.

In testimony whereof I affix my signature in presence of two witnesses.

OTTO W. SIEBENHAAR. [L.S.]
